OIL BURNING APPLIANCE

James L. Breese, Jr., Santa Fe, N. Mex.

Application December 24, 1934, Serial No. 758,980

10 Claims. (Cl. 158—92)

This invention relates to oil burning appliances, and has particular reference to an automatic valve mechanism for such appliances by which the quantity of oil flowing to the appliance for combustion purposes will be automatically regulated to maintain desired rates of combustion and uniform temperatures.

It is an object of the present invention to provide a simple yet efficient oil burner which may be employed for use in connection with domestic water heaters, stove and circulating warm-air heaters, garage heaters, poultry brooders and the like. In most of these applications, it is necessary that the burner shall operate at uniform combustion rates to produce for sustained periods of time substantially constant predetermined temperatures. Heretofore in oil burning appliances of this character, it has been customary to provide float actuated and other relatively complicated mechanisms for controlling the flow of oil at required rates to the burner, or to use thermostatically actuated electrical switches for opening and closing oil flow controlling valves. Such devices are rather complicated and are frequently the source of mechanical disorders which render the operation of such oil burning systems inefficient and unreliable.

It is, therefore, a primary object of the present invention to provide an improved oil flow regulating valve mechanism for oil burning appliances of the character referred to wherein the oil inlet casing of the appliance is provided with an oil flow passage and a valve seat with which is engaged a needle valve which normally obstructs oil flow past said seat toward the combustion region of the appliance, the said casing and valves being formed from metals having different coefficients of expansion which are interrelated and so disposed with respect to the combustion region of the appliance as to be responsive to combustion temperatures so that relative movement between said valve and its seat will take place to open and close said seat or passage to regulate the inflow of oil to the burner in accordance with the fuel demands of the burner.

For a further understanding of the invention, reference is to be had to the following description and the accompanying drawings, wherein:

Fig. 1 is a vertical sectional view taken through an oil burner and the oil flow controlling valve mechanism employed in connection therewith;

Fig. 2 is a similar view, the plane of the section being indicated by the line II—II of Fig. 1;

Fig. 3 is a detail sectional view on the plane indicated by the line III—III of Fig. 1;

Fig. 4 is a horizontal sectional view on the plane indicated by the line IV—IV of Fig. 1;

The oil burning apparatus disclosed in the accompanying drawings comprises a cylindrical retort 1 having horizontal rows of perforations 2 formed in the walls thereof. The bottom of the retort is seated within a metallic cup 3 having a bottom wall 4 of dished or concave form, the lower end of the retort resting on a horizontally disposed annular flange 5 of said cup, while the walls of the cup above the flange 5 closely and frictionally engage with the lower walls of the retort. Directly connected with the lower surfaces of the bottom wall 4 is a valve casing 6, preferably formed from cast aluminum or other metal of high heat conductivity. The casing is attached to the bottom wall 4 preferably by means of screws 7 and 8, the latter being provided with a central bore 9 which constitutes the admission passage through which oil is led into the bottom of the retort for combustion purposes.

The casing 6 includes an elongated substantially axially disposed passage 10, having its outer end internally threaded for the reception of the reduced threaded extension 11 of a valve seating fitting 12. This fitting connects with an oil supply pipe 13 through which liquid oil obtained from any suitable source, such as an elevated tank, passes under a suitable pressure head. The fitting 12 is formed at its inner end with a reduced orifice 14 which terminates in a seat 15, and adapted for engagement with the seat 15 to normally prevent flow of oil into the passage 10 of the valve casing, and the inlet bore 9, is the tapered end 16 of a needle valve 17. The needle valve is formed from a metal having a low coefficient of expansion such, for example, as Invar steel, whereas the casing 6 and its associated fitting 12 have a much higher coefficient of expansion. By the use of these materials and the construction and arrangement of the valve parts as disclosed, the heating of the valve casing and its fitting 12 above normal atmospheric temperatures causes the casing to expand, but since the valve 17 is stationarily supported within the passage 10 and is not effected to any appreciable extent by the increased temperature, an unseating of the valve takes place which allows passage of oil through the valve casing and into the bottom of the retort for combustion purposes.

The support of the valve 17 within the casing 6 is effected, in the form of my invention illustrated in Fig. 4, by providing the outer axial portion of the casing 6 with an internally threaded

socket for the reception of an externally threaded adjusting screw 18. This screw is provided with an axial outwardly projecting stem 19 equipped at its outer end with a hand wheel 20 by means 5 of which the screw may be rotated and advanced back and forth to various positions of adjustment in the casing socket. The stem 19 preferably receives a packing 21 to prevent fluid seepage. The inner end of the screw 18 terminates in a reduced 10 tubular extension 22 formed near the end thereof with openings 23 for the reception of a transversely extending pin 24, which passes through the outer end of the valve rod 17, and a coil spring 25 is arranged within the extension 22 15 and engages the end of the valve rod to normally force the pin 24 thereof into contact with the end walls of the elongated openings 23. The hand wheel 20 is provided with spaced lugs 26 which are arranged for engagement with a stationary stop arm 27 projecting from one end of 20 the valve casing 6, whereby the extent of adjustment of the screw 18 may be limited to control the amount of relative longitudinal movement which may take place between the valve rod and the 25 extension 22 of the screw 18, whereby to provide for adjustments in the position of the needle valve in order to provide for high, intermediate and low rates of combustion of fuel in the associated oil burning apparatus.

30 The upper end of the perforated retort 1 is provided with a fixed stationary cap 28 formed with an axially disposed vertically arranged burner tube 29. The annular wall of the cap 28 above the annular upper edge of the retort wall 35 is perforated as at 30, and above the perforations 30, the cap terminates in an outwardly and horizontally directed annular flange 31. Seated upon this flange is a horizontal top wall 32 of a stationary burner casing 33, which is of greater diameter than the retort 1 in order to provide an annular air circulating space 34. The bottom of the casing 33 is open to the atmosphere, so that air may enter the space 34, pass upwardly through the same, thence through the perforations 38 40 of the cap 28 and outwardly of the casing by way of an opening 35 in which is positioned the somewhat smaller upper end of the tube 29, whereby air may unite with the vaporized mixture leaving the retort by way of the tube 29 to produce 45 highly efficient combustion of the fuel.

In further carrying out the efficient combustion of the liquid fuel introduced into the bottom 50 of the retort, use is made of an air distributing head which comprises a tube 36 secured in connection with a socket 37 formed in the top wall 32 of the casing 33. The tube 36 extends upwardly from the socket 37 and terminates in a horizontally directed extension 38 provided with flanges 39, as shown in Fig. 2. Seated on the 55 flanges 39 is a perforated air distributing cone 40, which is held in place by the vertical screw 41, the said cone being provided with upper and lower horizontal rows of perforations 42. The distributing cone 40 acts to introduce a tertiary 60 body of air into the vaporized combustible mixture issuing from the top of the retort by way of the tube 36 in order to complete combustion of the mixture in an efficient manner with but minimum formation of smoke and carbon.

70 Additional control of the air supply to the burner is obtained by the provision of an air admitting elbow 43 which terminates within the retort in an axially disposed downwardly projecting open-ended nozzle 44, the open end of the latter 75 being spaced from the concave lower wall 4 of the

retort. The elbow 43 is secured as at 45 to the vertical wall of the retort and is connected with an air supply pipe 46, which may project through the wall of the outer casing 33. The pipe 46 is connected with fan means 46*, as illustrated in Fig. 2 for delivering air under pressure to the burner. The bottom of the casing 33 is provided with a strap 47, which is equipped with a thumb screw 48 disposed for engagement with the under side of the valve casing 6, whereby to retain the various parts of the burner assembly in rigidly secured fixed relationship.

In the operation of my improved oil burning apparatus, it will be observed that there exists a principle of reciprocal action between the oil admitting valve and the heat or temperature of fuel combustion. It will be noted that the valve 17 opens and closes entirely by reason of temperature changes which are developed in operation within the burner itself. When active combustion takes place within the retort, near its bottom wall 4, the temperature of the lower portion of the retort is increased, and this increased temperature is transmitted to the heat conducting material from which the valve casing is formed, 25 causing the valve casing to expand and move away from the tapered end of the valve rod to increase the flow of oil into the retort. This results in producing a greater body of oil within the bottom of the retort, which admixes with the air 30 drawn from the atmosphere through the perforations in the walls of the retort and through the air elbow 43 so that operating on the Bunsen principle, the region of combustion raises to its normal position, namely, that above the retort and 35 in substantially the plane of the distributing cone 40. Since the combustion region is then removed from the bottom of the retort, the latter becomes cooler, causing the seating or partial seating of the needle valve on its seat, and thereby arresting 40 or diminishing the inflow of oil to the bottom of the retort. The normal position of the visible flame of combustion is, as stated, at the mouth of the burner, as represented by the upper end of the tube 29, and the visible combustion 45 flame drops down into the retort only when the burner is receiving an insufficient quantity of oil. This action automatically brings about a replenishment of oil by variation in the vertical position of the fire. In other words, when the fire begins to be "starved" for lack of oil to support it, it drops from its normal position at the top of the burner down into the retort, where its proximity to the oil valve causes the valve to open and release more oil. As more oil is released into the burner, the fire is driven upwardly to its normal top position and the oil flow stops until again demanded by a "starved" fire.

The oil vaporizing control disclosed in connection with the retort is such as to obtain what is known as the hydroxylating process of burning oil. In this hydroxylating process, the oil is changed by the radiant heat of the burner from a liquid into a gas and mixed with air before combustion takes place, in much the same way as the Bunsen burner mixes the gas and air before combustion. In a burner of this type, where the unit is operating at the highest efficiency, there is no fire burning in the retort, which means that the floor of the retort or burner is relatively cool. As soon as a shortage of oil in comparison with the amount of air that is being constantly delivered takes place, a rarefied mixture in the retort occurs, which results in the lowering of the fire and the burning of the latter in the retort.

This presence of the fire increases the temperature on the floor of the burner or the retort, so that heat is transmitted in greater quantities to the aluminum valve casting comprising the casing of the oil valve and more oil is admitted to the burner to restore normal operation.

The air elbow is provided to inject an added amount of air to the retort immediately above the oil inlet. This produces a rarefied mixture which causes the fire to burn and in turn increases the temperature of the valve, producing an increased flow of oil. As soon as enough oil is admitted to the retort to cover its floor with a film or body of liquid oil, the valve is insulated by this body of oil, causing it to cool off and minimize or check oil flow.

The valve mechanism disclosed permits of the use not only of kerosene or equivalent, low boiling hydrocarbon oils but also the use of the better grades of fuel oil. The construction of the valve is such that it is practically impossible to permit the oil to build up flow obstructing quantities of paraffin wax or the like on the valve seat, since the needle valve in closing presses firmly against the seat to remove clogging deposits. In starting the appliance, it is merely necessary to inject by means of an oil can or the like, a small quantity of oil into the retort, which may be ignited by means of a taper. As soon as this pilot combustion has been effected, the further operation of the apparatus becomes automatic. The device operates to burn oil very economically so that the heater may be used as a substitute for apparatus burning more expensive types of fuels.

35 5. What is claimed is:

1. An oil burner comprising a retort provided with a closed bottom, perforated side walls and an open top, said top opening being of reduced size relative to the diameter of said retort, a short tube secured in the top opening, a casing open at its lower end surrounding said retort and spaced therefrom, said casing having a top wall formed with an axial opening of a size slightly greater than said tube to provide a space between the tube and the sides of said opening, the latter providing for the discharge of air from the top of said casing and for the admixture of such air with vaporized fuel constituents discharged from said tube, an air conduit extending through the side wall of said retort and casing and terminating in a downwardly directed nozzle, and an oil supply tube communicating with the lower interior portion of said retort.

2. An oil burner comprising a retort provided with a concave bottom wall, perforated side walls and a top wall having a reduced axial opening, a burner tube positioned in said opening, a casing open at its lower end surrounding said retort and spaced therefrom to provide an annular draft chamber, said casing having a top wall formed with an axial opening of a diameter slightly greater than said burner tube, the opening in the top wall of said casing providing for the discharge of air from the top of said draft chamber and into admixture with fuel constituents discharged from said tube, an air tube communicating with the draft chamber, a downwardly directed distributing cone connected with said air tube, said cone being positioned in axial registration with said burner tube, and an oil supply tube communicating with the lower interior portion of said retort.

3. An oil burner comprising a retort provided with a concave bottom wall, perforated side walls and a top wall having a reduced axial opening,

a burner tube positioned in said opening, a casing open at its lower end surrounding said retort and spaced therefrom to provide an annular draft chamber, said casing having a top wall formed with an axial opening for the discharge of air from the top of said chamber, said opening being of a diameter slightly greater than said burner tube and through which said tube projects, an air tube communicating with the draft chamber, a downwardly directed distributing cone connected with said air tube, said cone being positioned in axial registration with said burner tube, an air admitting conduit extending through the side wall of said retort and casing and terminating in a downwardly directed axially disposed nozzle spaced from said concave bottom wall, and an oil supply conduit communicating with the lower interior portion of said retort.

4. An oil burner comprising a retort provided with a closed bottom, perforated side walls and an open top, a casing open at its lower end surrounding said retort and spaced therefrom to provide an annular draft chamber, a valve casing of metal readily expandable when subjected to heat directly secured to the bottom of said retort in intimate heat exchanging relationship therewith, the interior of said valve casing communicating with the interior of said retort, said valve casing being formed with an internal valve seat, a valve rod rigidly supported at one end by said valve casing and engaging the valve seat at the other end, and an oil supply conduit connected with said valve casing at the end opposite that to which the valve rod is secured.

5. In oil burning apparatus, an oil vaporizing and combustion vessel of the hydroxylating type having a substantially closed bottom and an open top, a valve casing formed from a material possessing a relatively high thermal expansion factor carried by and in direct heat exchanging relationship with the bottom of said vessel, said casing being formed with an oil conveying passage establishing flow between a source of oil supply and the interior lower portion of the vessel, there being a valve seat in said passage, and valve means cooperative with said seat, said means being formed from a material possessing a relatively low thermal expansion factor as compared with that of said casing, whereby the flow of oil through said passage increases or decreases in direct proportion to the increase or decrease in the temperature of the bottom of said vessel.

6. In an oil burner of the hydroxylating type having a closed bottom, perforated side walls and an open top, a fuel control valve comprising a hollow body disposed in heat exchanging relationship with the burner bottom, said body being formed of metal having a high coefficient of expansion, a seat provided within said body adjacent the inlet thereto, the interior of said body being in open communication with the interior of said burner, and an elongated needle valve positioned within said body and connected at one end therewith, the opposite tapered end of said valve being in engagement with said seat, said valve being formed of metal having a low coefficient of expansion.

7. In an oil burner of the hydroxylating type having a closed bottom, perforated side walls and an open top, a fuel control valve comprising a hollow body rigidly secured directly to the bottom of the burner, said body being formed of a metal having a high coefficient of expansion, a seat provided within said body adjacent the inlet thereto, the interior of said body being in open

communication with the interior of said burner, and an elongated needle valve positioned within said body and connected at one end therewith, the opposite tapered end of said valve being in engagement with said seat, said valve being formed of a metal having a low coefficient of expansion.

8. In an oil burner of the hydroxylating type having a closed bottom, perforated side walls and an open top, a fuel control valve comprising a tubular body secured intermediate of its ends to the bottom of said burner, said body being formed of a metal having a high coefficient of expansion, a seat provided within said body adjacent the inlet end thereof, the interior of said body being in open communication with the interior of said burner, and a needle valve disposed within said body and secured at one end thereto, the opposite tapered end of said valve being in engagement with said seat, said valve being formed of a metal having a low coefficient of expansion.

9. In an oil burner of the hydroxylating type having a closed bottom, perforated side walls and an open top, a fuel control valve comprising a tubular body carried by the bottom of said burner, said body being formed of a metal having a

high coefficient of expansion, a seat provided within said body adjacent the inlet end thereof, the interior of said body being in open communication with the interior of said burner, and a needle valve disposed within said body and resiliently secured at one end thereto, the opposite tapered end of said valve being in engagement with said seat, said valve being formed of a metal having a lower coefficient of expansion than that of said body.

10. In an oil burner of the hydroxylating type having a closed bottom, perforated side walls and an open top, a fuel control valve comprising a hollow body disposed in direct heat exchanging relationship with the bottom of said burner, said body being formed of a metal having a high coefficient of expansion, a seat provided within said body, the interior of said body being in open communication with the interior of said burner, and a valve rod disposed within said body and adjustably secured at one end thereto, the opposite end of said valve rod engaging said seat, said valve rod being constructed of a metal having a lower coefficient of expansion than that of said valve body.
